(57) **CLAIM**

The ornamental design for a clipper blade protector, as shown and described.

DESCRIPTION

FIG. 1 illustrates a front perspective view of a clipper blade protector and shown attached to a hair clipper.

FIG. 2 illustrates a front perspective view of the clipper blade protector of FIG. 1.

FIG. 3 illustrates a bottom perspective view of the clipper blade protector of FIG. 1.

FIG. 4 illustrates a top view of the clipper blade protector of FIG. 1.

FIG. 5 illustrates a bottom view of the clipper blade protector of FIG. 1.

FIG. 6 illustrates a front view of the clipper blade protector of FIG. 1.

FIG. 7 illustrates a rear view of the clipper blade protector of FIG. 1.

FIG. 8 illustrates a right side view of the clipper blade protector of FIG. 1; and,

FIG. 9 illustrates a left side view of the clipper blade protector of FIG. 1.

The broken lines illustrate the environment of the clipper blade protector and form no part of the claimed design.

1 Claim, 9 Drawing Sheets
